NILS ALFRED UNGER, OF VINTERVIKEN, ASPUDDEN, SWEDEN.

PROCESS AND DEVICE FOR THE DEVELOPMENT, FIXING, WASHING, ETC., OF
PHOTOGRAPHIC OR CINEMATOGRAPHIC FILMS OR THE LIKE.

Application filed March 6, 1926, Serial No. 92,811, and in Sweden November 13, 1925.

This invention relates to a process and devices for the treatment of films, especially sensitive exposed films, which are to be developed, fixed, washed, or subjected to 5 similar treatment with fluids.

The invention can be applied both to ordinary camera films (including roll films and cut films) and to cinematographic films.

A previously known device for the development etc. of films is the use of special ribbons with the aid of which the film is wound up on a roller so as not to be exposed to light, the film being kept in position by its own tension without any attachment to 15 the ribbon.

In accordance with the present invention the film is removably fastened to a protective ribbon or strip serving as a support for it, which strip may consist, for example, of 20 celluloid, paper, metal etc., whereupon the ribbon together with the film is rolled up in such a way as to leave a space between the different layers or windings of the roll, and is subjected to the action of the fluid, for 25 example a developing, fixing, or washing solution, with which the film is to be treated.

In order to make plain the invention, some examples of a device, suitable for the purpose, are shown in the appended drawing.

30 Figure 1 shows the ribbon intended as a support with the film removably fastened to it, in perspective, partly rolled up.

Figure 2 shows the same device seen from above.

35 Figure 3 shows in plane and Figures 3^a in cross section another arrangement of the ribbon or strip serving as a support or holder.

Figures 4 and 4^a show in a similar manner 40 still another form of the arrangement.

In the different figures the corresponding parts are designated with the same ciphers. The invention will first be described with reference to Figures 1 and 2.

45 1 designates a thin ribbon or belt, serving as a support or holder, which may be made of celluloid, paper, metal, or other material suitable for the purpose. 2 designates the photographic film. 3 designates fastening devices arranged in the support for detachably fastening the film 2 to the support 1. According to the example shown in Figures 50 1 and 2, the fastening devices are formed by the punching of tongues out of the support 1, which tongues are bent outwards in

the manner indicated in Figure 1, so as to form a series of elastic hooks on either edge of the support. Between these hooks or fastening devices the film 2 is removably 60 pressed in. This may be effected most suitably in the following manner:—The support 1, which should preferably have been wound up into a roll, is unwound, and at the same time the photographic film 2—while it is being unwound from the roller on which it is 65 coiled, if it is a roll film—is pressed in between the fastening devices 3. Concurrently with or after the fastening of the film 2 in place on the supporting strip 1, the support 1 with the film 2 fastened to 70

it is wound up into a roll in the manner shown in Figure 1, so that the fastening devices 3 at the same time serve, so to speak, as spacing devices, whereby the different coils of the roll are kept at a certain 75 distance from one another, so that between these coils spaces 14 are formed, thereby facilitating the free access of the fluid to the film 2, the sensitive side (image surface) of which faces away from the support 1. If, as 80 above indicated, the support 1 has been coiled into a roll from the outset, it has, owing to its inherent tension, a tendency to coil up again according as it is unwound for the fastening of the film 2 onto it. It should 85 be obvious from the above that the rear side of the support 1 will not come into contact with the sensitive surface of the film 2, but will be kept at a suitable distance from it. The film, arranged in this manner, can be 90 subjected to treatment with the fluids in question without requiring the use of cumbersome vessels and without tiresome manipulations.

The invention is particularly well adapted 95 for so-called time development, but it should be obvious that the roll formed by the support and the film attached to it may also be arranged in a different position. The roll may, of course, be transferred from one bath 100 to another as desired.

On the termination of the treatment, the film 2 can easily be detached from the support by gently pulling the film off it, when the elastic hook formed tongues 3 yield, so 105 that the film is detached from the support without any risk of its being spoilt. The support 1 may thereupon be rolled up and preserved for further use. In the case of cut films, one film after the other is fastened 110

in the manner above indicated to the support. With a view to facilitating the more effective action of the fluid on both sides of the film, the support 1 may be provided with 5 perforations 4 of a form suitable for the purpose (see Figure 1), or, if desired, may be provided with corrugations 5, as is indicated in Figures 3 and 3^a, or with both.

In the example described above, the fastening devices have been shown to consist of 10 tongues 3 punched out of the support, but they may be formed in another way, for example of the material itself of the support, or else by suitable devices fitted to it. In 15 Figures 3 and 3^a, for example, the fastening devices are shown to consist of flange-like rims or collars 6 arranged at the edges of the film. In order to facilitate the winding up of the support, the edges in this case 20 should be provided with transverse cuttings 7. The said collars or flanges 6 form yielding fastening devices, between which the film 2 can be detachably fastened by gently pressing on it. Figures 4 and 4^a show an example 25 of fastening devices which are not made in one piece or integral with the support 1, but consist, for example, of cylindrical beads or similar bodies 8, which by threads 9 or other suitable means are fastened to the support, 30 so as to form a row running lengthwise along either edge of the support. It should be obvious that fastening devices may be formed in many other ways.

Having thus described my invention I declare that what I claim is:—

- 35 1. A device for the treatment of sensitized film comprising a flexible ribbon support and means disposed along the lateral margins thereof adapted to removably secure a film to said support.
- 40 2. A device for the treatment of sensitized film comprising a flexible ribbon support and means disposed along the lateral margins thereof for removably securing a film to said support, said means projecting from the surface of said support.

3. A device for the treatment of sensitized film comprising a flexible belt and frictionally gripping means disposed along the lateral margins thereof, for removably securing 50 a film to said belt, said means being adapted to position the film upon said belt and hold the lateral edges thereof in place.

4. A device for the treatment of sensitized film comprising a flexible belt and frictionally gripping means integral with said belt and disposed along the lateral margins thereof for removably securing a film to said belt, whereby the film is held against said belt by its edges being pressed between 55 the lateral rows of gripping means.

5. A device for the treatment of sensitized film comprising a flexible ribbon support and means disposed along the lateral margins thereof for removably securing a film 60 to said support, said means comprising a plurality of flexible tongues turned up from separated portions of said margins.

6. A device for the treatment of sensitized film comprising a flexible ribbon support 70 adapted to be rolled up and means disposed along the lateral margins thereof for removably securing a film to said support, said means projecting from the surface of said support whereby the superposed layers of 75 said support, when rolled up, may be spaced from each other.

7. The method of treating sensitized film which comprises removably securing a film to a flexible ribbon support by pressing the 80 edges of the film between parallel rows of frictionally gripping tongues disposed along the marginal edge portions of the support and projecting from the surface thereof, winding the support into a roll with the successive turns spaced from each other, and thereafter immersing the thus formed cellular roll into the operating fluid.

In witness whereof I have hereunto set my hand.

NILS ALFRED UNGER.
